(57) **CLAIM**

I claim the double bowl sink, as shown and described.

DESCRIPTION

FIG. 1 is a perspective view of a double bowl sink in accordance with the invention.

FIG. 2 is a top elevation view of the double bowl sink shown in FIG. 1; and,

FIG. 3 is a cross-sectional view of the double bowl sink shown in FIGS. 1 and 2 and is taken about the line 3—3 shown in FIG. 2.

Broken lines shown in the drawings are environment and do not form part of the claimed design. The broken line(s) adjacent to the shaded area of the double bowl sink define the bounds of the claimed design and form no part thereof.
